HYDRAULIC MOTION-TRANSMITTING
MECHANISMS FOR PRINTING MA-
CHINES AND OTHER PURPOSESHarold G. Barrett and Godfrey E. Thomson, Chi-
cago, Ill., assignors to Reynolds Printasign Co.,
Chicago, Ill., a corporation of Illinois

Application December 10, 1949, Serial No. 132,382

33 Claims. (Cl. 197—2)

1

This invention relates generally to hydraulic motion-transmitting mechanisms and particularly hydraulic precision feed devices. More particularly the invention relates to an improved hydraulic or fluid pressure feed mechanism designed primarily for use in conjunction with printing machines of a certain type hereinafter identified.

A sign and card printing machine such, for example, as that illustrated and described in U. S. Letters Patent No. 2,115,692, granted to Robert J. Thorn on April 26, 1938, necessarily includes feed mechanism which automatically shift the card laterally, following the printing of each letter or other character, except the final letter or character of each line; and such a feed mechanism must be capable of moving the card, in each instance, to an extent which will afford precisely the correct interval between consecutive letters or characters. If the required spacings were identical, irrespective of the paired letters or characters, as in the case of a conventional typewriter, there would be no special problem because uniform spacing can easily be achieved through the use of an escapement mechanism. But uniform spacing will not answer the purpose in a sign printing machine of the kind here dealt with because the type pieces are designedly of different widths, for which reason the spacing which follows each letter or character must be made to harmonize with that particular letter or character. Otherwise, the visual effect would not be satisfactory.

The feed mechanism heretofore employed, such, for example as that shown and described in the above-identified Thorn patent, is capable of affording accurate spacing provided the operator continuously exercises appropriate care to avoid overthrow of the card-carrier; but in their zeal for speed many operators are prone to move the actuating arm so vigorously on the return stroke that overthrow almost inevitably results; and frequently the operators seem unable to overcome that fault without retarding all stages of the operation to a like degree—thereby substantially reducing their output over and above what would normally result from a mere reduction of the speed at which the actuating arm is returned.

One of the principal objects of this invention is to provide a feed mechanism which is suitable for use in conjunction with a printing machine

2

of the kind referred to, and which is both highly accurate and substantially proof against overthrow.

Another important object is to provide a feed mechanism of the above-indicated character which will retain its accuracy and remain in good working condition, without attention, for long periods of time.

It also is an object to provide a highly accurate hydraulic feed mechanism capable of being preset and substantially proof against overthrow and adaptable for general application, which is to say, not limited in utility to the printing art.

In the drawings which accompany this specification:

Fig. 1 is a perspective view of a sign or display card printing machine embodying the subject invention;

Fig. 2 is a plan view of the machine;

Fig. 3 is a front elevation, partially in section;

Fig. 4 is a side elevation;

Fig. 5 is a perspective view of the type-case carriage;

Fig. 6 is an enlarged section taken on line 6—6 of Fig. 2;

Fig. 7 is a section taken on line 7—7 of Fig. 6;

Fig. 8 is a plan view, partially in section, showing the inking rollers;

Fig. 9 is a perspective view of the pan in which the inking rollers are mounted;

Fig. 10 is a schematic perspective view designed to clarify certain details which would not otherwise be readily comprehensible;

Fig. 11 is an enlarged sectional view taken on line 11—11 of Fig. 7;

Fig. 12 is a lengthwise section of the actuating arm and shows a part of the pushbutton mechanism for opening the fluid check valve of the feed mechanism to enable return movement of the card-carrier;

Fig. 14 is a sectional view taken on line 14—14 of Fig. 13; and

Fig. 15 is an elevation of the lower end portion of the driving cylinder.

General description

Referring more especially to Fig. 1, the major components of the sign printing machine therein illustrated are: a rectangular base A to opposite

sides of which are rigidly attached two identical upstanding track-supporting members B; two parallel tracks C of channel cross-section fixedly secured to the supporting members B; a carriage D mounted on the tracks C and movable therewith in a horizontal plane parallel to the top surface of the base A; a type-case E mounted on the carriage D and movable therewith in a horizontal plane parallel to the top surface of the base and perpendicularly to the path of movement of the carriage D on tracks C; a bridge F bolted to the track supporting members B and overlying the base; a type-actuating and spacing mechanism identified as a whole by reference letter G and supported by the bridge F; a card-carrier plate H lying on the top surface of base A and guided for rectilinear movement transversely of the base, as indicated by the double-headed arrow; a piston and piston rod J connected to the rear margin of the card-carrier plate H; and a fluid pressure cylinder K in bore of which the piston and rod J are mounted. A blotter 28 is secured, as by adhesive tape, to the top surface of the plate H and underlies the carriage D and type-case E; and a card of any appropriate size, not shown, upon which the printed matter is to be impressed is secured, usually by means of adhesive tape, to the upper surface of the blotter.

The type-case E houses a large number of vertical type-bars, each carrying a type-face which is soldered or otherwise attached to its lower end and each normally held in an elevated position by means of a biasing spring. The top of the type case is in the form of a plate 24 having a large number of circular apertures 22 each of which is axially aligned with one of the vertical type-bars therebelow.

The mechanism G includes a vertical plunger 23 which is disposed above the plate 24 and movable downwardly in response to manual rotation of an actuating lever arm 24 to enter a selected one of the apertures 22 to engage and depress the type-bar in line therewith and thus impress the corresponding letter or character on the upper surface of the card being printed.

The type-case E is movable manually by means of a handle 26 to enable the operator to position any selected one of the apertures 22 in line with the plunger 23; and after each letter or character is printed the card-carrier plate H is automatically shifted the distance necessary to bring about the correct spacing. The means by which the spacing is accomplished accurately, irrespective of any lack of precaution on the part of the operator, and whereby the spacing can be variably predetermined, constitutes the principal subject matter of the present case and will be described in detail later.

As will subsequently be shown, the card-carrier plate H is movable not only in the transverse direction to effect the required spacing between the letters of a given line, as indicated by the double-headed arrow on Fig. 1, but also is movable, together with the blotter 28 and the card thereon, in the direction perpendicular to the double-headed arrow to effect spacing between consecutive lines, when a sign or display card is to comprise more than a single line. The latter movement is accomplished by turning a hand knob L attached to a shaft extending transversely of the base, below the top surface thereof, and equipped with a pinion which engages a rack connected to and movable with the card-carrier plate.

The base A

The base A is fabricated of sheet metal and structural shapes, preferably aluminum, and comprises a horizontal top plate 30 and vertical side, front and rear walls 31 of channel section, Fig. 7, together with a corner moulding 32 of angle section. Ordinarily, the base is mounted on a table or bench and may conveniently be provided with four short adjustable legs 33 by means of which the top surface can be leveled. As most clearly shown in Fig. 10, the top plate 30 has an elongate slot 34 the forward end of which terminates rearwardly of plunger 23 and through which extends a rectangular metal block 36—see Figs. 6, 7 and 10. To the bottom of block 36 is attached, by means of screws 37, an elongate bar 38 which serves as a carrier for two rollers 39 spaced apart lengthwise of the bar and closely but movably fitted between the upright flanges of a channel-shaped guide member 40 the ends of which are connected to the front and rear walls 31 of the base, by means of which they are supported.

The card-carrier plate H

The rectangular card-carrier plate H rests on the top plate 30 of the base A and carries at its rear margin two spaced apart rollers 42—see Fig. 6—which are positioned between the depending flanges of a channel-shaped guide member 43 carried by a supporting plate 44 secured by screws 45 to the top side of block 36. Since the rollers 39 and 42 fit closely within their respective guides 40 and 43, it will be apparent that the card-carrier plate H is held firmly against twisting motion relatively to the top surface of the base while still capable of being moved bodily in all directions parallel to said top surface.

A suitable fitting 47 attached to the rear margin of plate H is fixedly connected to the exterior end of piston rod J which, as previously stated, extends into the cylinder K and functions as a piston therein—see especially Fig. 10—said cylinder being supported near one end by the block 36 and at the other end by a fitting 48 carried by the channel member 43. It will now be evident that if oil or other incompressible fluid under pressure is admitted to cylinder K, the piston rod J will be moved proportionately to the volume of fluid so admitted and that the card-carrier will be moved the same distance transversely of the base. Reverse movement of the card-carrier is accomplished manually, and for that purpose a handle 49 is attached to the carrier at the left-hand side thereof, as plainly shown in Figs. 1 and 10.

The track C

The two parallel tracks C are channel-shaped members to the lower flanges of which are secured steel rails 50 of round cross-section, as best shown in Fig. 7. Such rails fit the correspondingly grooved wheels 51 of the carriage D and serve to prevent lateral displacement of the carriage while permitting free movement therewith.

The carriage D

The carriage D, shown separately in Fig. 5, consists of two parallel side members 52 and 53 of channel cross-section—see Fig. 6—and two mutually parallel end members 54 and 55, likewise of channel cross-section, secured to and bridging the ends of members 52 and 53. The member 54 is long enough only to span the dis-

tance between members 52 and 53 whereas the member 55 is made much longer in order to further stabilize the carriage against twisting. The wheels 51 are four in number and are rotatable on trunnions rigidly affixed to the members 54 and 55. The lower flange of member 52 carries a rail 56 of square cross-section while the lower flange of member 53 carries a rail 57 which is of round cross-section. The rails 56 and 57 serve to support the type-case E through the medium of its mounting wheels 58 and 59—see Fig. 6.

The type-case E

The type-case E is a rectangular metal box including side and end walls 60 together with a horizontal bottom plate 61 and the previously mentioned top plate 21 in which are drilled the several round apertures 22 for reception of the plunger 23. Also formed in the top plate 21 are a large number of indentations or notches 63—see Fig. 13—each associated with and situated adjacent one of the apertures 22. These notches are formed in a press by means of a punch of rectangular end configuration which cuts on three sides only to produce, in each case, a shoulder 64 and a sloping surface 65. As will later be made clear the location of each shoulder 64 relatively to its individually associated aperture 22 determines the length of the spacing which will follow each operation of the immediately related type-bar. Thus, the spacing to follow each letter or character is predetermined by the location of its related shoulder 64, subject, however, to an additional provision by means of which the spacing can be altered independently.

The bottom plate 61 has square openings 65 corresponding numerically and in vertical alignment each with one of the round apertures 22 in the top plate 21; and slidably positioned in each square opening 65 is a type-bar 66 of square cross-section, to the lower end of which is attached a type-face 67. A coil spring 68 encircles each type-bar 66 and presses upwardly against a washer 69 seated in a groove formed in the upper end portion of the type-bar. Thus, each type-bar 66 normally is held in an elevated position by its retracting spring 68, in which circumstance the type-face is well above the card upon which the printed matter is to be impressed. The upper end of each type-bar 66 is turned to form a pilot 66a proportioned to fit a recess 23a—see Fig. 14—in the lower end of the plunger 23, which provision insures that the type-bars will maintain their vertical alignment when being depressed.

The ink rollers

A pan 70, shown separately in Fig. 9, is bridged across and supported by the members 52 and 53 of carriage D—see Figs. 6 and 8. Said pan comprises a bottom plate 71, two upstanding end flanges 72 and 73, and two upstanding side flanges 74 and 75. The bottom plate 71 has a central opening 76 which is bounded by upstanding flanges 77, 78, 79 and 80. Secured to each of the flanges 72 and 73 and projecting outwardly therefrom are six studs 82, below each of which is located a vertically elongated slot 83, each designed to receive one end of a rod 84. The rods are suspended on tension springs 86 which is best shown in Fig. 6 have their upper ends anchored to the studs 82. The rods 84 are non-rotatable and serve as supports for inking rollers, which latter are identified by reference numerals 87, 88, 89, 90, 91 and 92—see Fig. 8.

Each roller comprises a long tubular bushing 93 rotatably mounted on its supporting rod and a rubber covering of circular cross-section. Each bushing 93 is of a length such that it is capable of limited lengthwise movement along its supporting rod. The axes of the several rollers are disposed angularly to the path of movement of the type-case relatively to the carriage D, as clearly shown in Fig. 8, and each roller is held by the suspension spring 86 at a level determined by the upper extremities of the slots 83, such that it makes firm contact with the type-faces 67. It will be observed that the two ink rollers 89 and 90 have rubber coverings which extend completely across the array of type whereas the remaining rollers are of lesser length—one pair spanning about one-half the array and the other pair about one-third. The reason for this is that the largest type, requiring the greatest amount of ink, are grouped on one side of the type-case where they make contact with all six rollers, whereas the intermediate size type are grouped midway of the width of the type-case and make contact with four rollers, while the small type are grouped on the other side of the type-case and make contact with only two rollers. By virtue of the angular dispositions of the ink rollers, the movements of the type thereover causes them to shift lengthwise of their supporting rods, first one way and then the other, depending upon the direction of movement of the type-case and, as a consequence, all portions of the roller peripheral areas are brought into contact with the type-faces. The opening 76 serves only to provide clearance for the actuated type-bar.

The type-bar actuating mechanism

A head casting 95 is bolted to and supported by the central portion of the bridge F and serves as a mounting and housing for numerous mechanical parts including the plunger 23 which, as clearly shown in Fig. 14, is slidably journaled for vertical movement in bushings 96 and 97. A casting 98 secured to plunger 23 has a laterally projecting trunnion 99 which is connected to the lower end of a pitman 100, the upper end of which is pivotally connected at 101, Fig. 14, to a quadrant 102. The latter is keyed to a tubular shaft 103 which is journaled in bushings 104 and 105—see Fig. 11. The actuating arm 24 is keyed or otherwise firmly secured to the outboard end of shaft 103 and is equipped with a laterally projecting handle 25 at its distal end. It will be apparent that when the handle 25 is moved downwardly toward the operator, the plunger 23 likewise will move downwardly in response thereto to depress whichever type-bar may at the moment be positioned in registration therewith. A tension spring 107, Fig. 7, counterbalances the weight of the plunger and actuating arm and serves yieldably to retain those parts in their normal elevated positions.

For the purpose of restraining plunger 23 against rotation the casting 98 is formed to include an arm 98a which carries a spring-pressed plunger 108. The latter which is against the adjacent surface of a plate 109 secured to head casting 95. Such casting also is provided with a trunnion upon which is mounted a roller 110 which likewise bears against the adjacent surface of plate 109. Since the plunger 108 and roller 110 are located on opposite sides of the plunger 23, it will be evident that they operate conjointly to prevent rotation of casting 98 and plunger 23.

The hydraulic feed mechanism

The previously mentioned hydraulic cylinder K is connected through the medium of a swivel joint 112—see Fig. 10—and a flexible hose 113 to a fitting 114—see Fig. 14—which is detachably connected with the lower end of a vertical cylinder 116 by means of a screw cap 117. The latter is threaded to the lower end of the last-mentioned cylinder.

Cylinder 116 is supported by the head casting 95 in the manner clearly illustrated in Fig. 14, with its upper portion disposed within a reservoir 118 formed in the casting 95 and designed to contain a substantial quantity of oil or other suitable incompressible fluid.

A driving piston 120 is vertically reciprocable in the bore of cylinder 116 and is biased upwardly by a compression spring 121 which bears downwardly against the cap 117 and upwardly against a flange at the upper extremity of a sheet metal cup 122 which, in turn, is seated against an annular shoulder inside the piston. A ball check valve 123 is lightly held against a valve seat 124 by a spring 125 and is easily displaced to pass fluid downwardly through passageway 126 from the reservoir 118 when the piston ascends—the cup 122 being apertured at its lower end to afford communication between the passageway 126 and the bore of fitting 114 by way of several discharge ports in the form of small orifices 128 drilled through the wall of cylinder 116 at its lower end—see Fig. 15. Fluid passes between the reservoir 118 and the interior of cylinder 116 through a number of ports 129 in the cylinder wall and thence into and out of the bore 130 of piston 120 through ports 131 drilled through the wall of the piston in proximity to the ports 129.

In Fig. 14 the piston 120 is shown in its fully depressed position, and it will readily be seen that if it is allowed to rise under the impetus of spring 121 fluid will pass from reservoir 118 through ports 129 and 130 and thence past ball check valve 123 into passageway 126, thus keeping the line between the driving and driven pistons constantly filled with fluid, even though the driven piston is not retracted concurrently with the upward stroke of the driving piston.

When the piston 120 has completed an upward stroke under the impetus of spring 121, and is thereafter pressed downwardly, its latter movement will be followed by the driven piston and rod J, and the displacement of one piston will correspond precisely with that of the other, except for a possible slight amount of leakage past the ball check valve 123 which may occur at the beginning of each downstroke of piston 120—which leakage, if any, is entirely harmless since it is of constant magnitude and therefore does not detract from the accuracy of the resultant spacing.

Each downstroke of piston 120 causes the driven piston J and card-carrier H to move transversely of the base A a distance corresponding to a predetermined spacing between consecutive letters or characters, which spacing distance is variable by changing the stroke of piston 120. The mechanism by which the length of the piston stroke is automatically controlled consonantly with the spacing requirement for each individual letter or character is described.

When a line of printing has been completed and a second line is to follow, it generally is necessary to return the card-carrier H and the driven piston either to the previous starting

point or some intermediate point, according to the layout of the sign, and the return movement is effected manually by the operator through the medium of handle 49. But in order to retract the driven piston it is necessary to allow the fluid in the line to move back through the driven piston into reservoir 118, which could not be done with the ball 123 seated; and it would be a slow operation even with the ball 123 unseated if the fluid had to return through the constricted orifices 128. For the purpose of unseating ball 123 as a preliminary to a return movement of the card-carrier, there is provided a rod 135 which is slidably fitted in an axial bore in piston 120 and rests upon ball 123. The upper end of rod 135 extends beyond the upper end of piston 120 and is positioned for engagement by a finger 136 which is rigidly secured to and carried by a shaft 137 extending axially through and rotatable within the bore of the tubular shaft 103. A second finger 138 rigidly secured to shaft 137 is located interiorly of the actuating arm 24, as best shown in Figs. 11 and 12, and extends through an arcuate slot in shaft 103 to engage one end of a plunger 140 having at its outer end a pushbutton 141. The plunger 140 is normally retracted by a spring 142 seated in a recess in the distal end of arm 24 and bearing against the under side of pushbutton 141.

When the pushbutton is depressed by the operator while the actuating arm 24 is in its elevated position the resultant movement of plunger 140 will effect through finger 138 an angular movement of shaft 137 which, in turn, will bring about a downward movement of finger 136 sufficient to depress the rod 135 and thereby unseat ball 123. The operator depresses pushbutton 141 before attempting to retract the card-carrier and holds the same depressed until the retraction of the card carrier is completed.

The cap 111 is provided with a number of parallel passageways 144 establishing one-way communication between the bore 145 of fitting 114 and a well 146 the upper rim of which forms a seat for a ball check valve 148, which latter functions to prevent discharge of fluid from cylinder 116 via passageways 144 while allowing unimpeded flow therethrough in the opposite direction. Thus, with ball 123 unseated the card-carrier can easily be retracted, because the returning fluid is not impeded by the constriction or small total area of orifices 128.

A casting 150 is rigidly connected to the upper end of piston 120 and vertically reciprocable therewith and has a horizontal top surface 151, a portion of which functions as a track for a roller 153 on a trunnion 154 that is carried by quadrant 102. When the roller 153 moves with quadrant 102 in a clockwise direction from the position in which it is shown in Fig. 14, it obviously follows an upwardly trending arcuate path, and the driving piston 120 (which normally is held in its downmost position by roller 153, as depicted in Fig. 14) is consequently allowed to rise under the impetus of its retracting spring 121; and so far as the opposition of roller 153 is concerned, the said piston would rise to a fixed maximum elevation each time the plunger 123 is brought down in response to rotation of the actuating arm 24. That, on its face, would not be permissible because it would result in large uniform forward strokes of the driving piston and concomitant large uniform forward movements of the driven piston and card-carrier and, accordingly, would not afford the vari-

ant spacings between consecutive letters or characters which, as we have previously pointed out, must be had. Hence, it is necessary to introduce some medium which will serve to restrict each upstroke of driving piston 120 to a limit corresponding with the desired or predetermined measure of the spacing next in order; or, viewed broadly from the standpoint of the ultimate objective, some medium capable of correctly predetermining the length of each forward stroke of the driving piston—the latter being the immediate criterion as respects the degree of advance of the card-carrier.

The casing 150 includes an upstanding flange or rib 152, the rear face of which, as viewed in Fig. 14, lies substantially in the vertical plane of the adjacent face of roller 153 and thus serves to prevent rotation of casting 150 and piston 120 in response to the movement of the roller along the top surface of the casting.

The spacing control mechanism

Referring more especially to Fig. 13, a bellcrank 158 is supported by head casting 95 on a fulcrum 159 and comprises a horizontal arm 160 and a vertical arm 161. The horizontal arm 160 is apertured at its distal end to form a pocket 162 in which is positioned a steel ball 164 resting on the top surface 151 of casting 150; and a long adjusting screw 165 threaded into the bellcrank at 166 has a tapered end 167 bearing against the upper surface of ball 164 and serving to lock the same in place. The outer end of screw 165 carries a knob 168 by which the screw can be rotated manually; and said knob has a graduated scale 170, preferably with numerical indicia, which registers with the adjacent pointed end of a pin 171, the other end of which has a nipple projecting into an opening in a lug 172 forming an integral part of the bellcrank, and a flange 173 abutting the said lug. The pin 171 passes loosely through an opening 174 in an adjacent wall of the head casting and a compression spring 175 encircles said pin and presses the same against the lug 172, thus biasing the bellcrank clockwise, as viewed in Fig. 13. It will now be seen that by rotating screw 165 the ball 164 can be pushed downwardly or vice-versa relatively to the distal end of the bellcrank arm 160, thus bringing about a micrometric rotation of the bellcrank in a direction determined by the direction of rotation of the screw, and it will be apparent that the scale 170 affords a medium by which the operator can gauge the angular adjustment.

Pivotedly connected at 171 to the lower end of bellcrank arm 161 is a dog 172, the heel of which normally abuts a stationary stop arm 173—see Fig. 13—against which it is held by the pressure of spring 175 acting on the bellcrank—the stop arm 173 being a long rod anchored at its upper end to the head casting 95 from which it depends. The free end or toe of dog 172 is normally positioned above and clear of the top plate 21 of the type-case and consequently does not interfere with movements of the type-case in the horizontal plane; but when the plunger 23 is brought down to enter one of the type-case apertures 22 as a result of the previously-described rotation of the actuating arm 24 and shaft 103, the piston 120 and casting 150 are elevated by spring 121, thus causing the bellcrank 158 to be rotated in a counterclockwise direction, Fig. 13, about its fulcrum 159. Thereupon the heel of dog 172 moves away from stop arm 173 and its free end or

toe drops into contact with the top plate 21. As previously explained, the top plate 21 has a notch 63 and shoulder 64 in association with each aperture 22 and each of these is located to line up horizontally with the dog 172 when its associated aperture 22 is vertically aligned with the plunger 23. Therefore, as the bellcrank 158 continues its counterclockwise rotation during the descent of the plunger 23, the toe of dog 172 engages the shoulder 64; and since the type-case is restrained against lateral displacement by virtue of its interlocking engagement with plunger 23, the rotation of the bellcrank is arrested, and likewise the upward movement of piston 120 and casting 150, because the bellcrank, acting through ball 164, then functions as a stop to limit the upward movement of said piston and casting. This does not in any way inhibit further rotation of quadrant 102 or the downward movement of plunger 23, as will be evident from the fact that roller 153 is free to continue its upward arcuate course irrespective of the discontinuance of upward movement of casting 150. At this juncture it will be apparent that the location of shoulder 64 relatively to its associated aperture 22 determines the degree of rotation of bellcrank and thus, in turn, determines the extent to which the piston 120 will rise. And it will be remembered that the length of the piston upstroke determines the length of its subsequent downstroke and thus the extent of resultant spacing movement imparted to the card-carrier.

Vertical rod 175—see Fig. 7—is slidably journaled in a lug 176 on bellcrank arm 161 and is biased downwardly by a spring 177. The lower extremity of rod 175 overlies the dog 172 to one side of its fulcrum and is thus adapted to bias the dog rotationally in the clockwise direction, as viewed in Fig. 7, thus insuring against the possibility of the dog failing to move into engagement with the top plate upon breaking contact with the stop arm 173. Connected to the upper end of rod 175 is a frustro-conically shaped head 178, the lower rim of which overlies a lug 180 forming an integral part of the casting 98. Normally the head 178 rests upon the lug 180, thus relieving the dog 172 from the pressure of spring 177, as well as the weight of rod 175 and head 178; but as the plunger 23 descends it carries with it the casting 98, thereby allowing rod 175 to move downwardly and bring pressure to bear against the dog. During the subsequent up movement of plunger 23 the lug 180 lifts the rod 175, removing from the dog the pressure of spring 177 and the weight of rod 175 and head 178 so that when the heel of the dog again makes contact with the stop arm 173 the latter will rotate the dog back to its normal position, Fig. 7, without having to overcome any resistance other than that due to the dog itself.

Mode of operation

The first step in a sign or card printing operation is to push the carriage D, together with the type-case E, to the rear in order to uncover the card-carrier H. Then the operator attaches a blank card to the blotter 29, usually by means of adhesive tape, aligning the same with an edge of the blotter. Thereafter, if necessary, the operator moves the card-carrier forward or back by rotating knob L, thereby appropriately positioning the card in one direction with reference to the plunger 23. Following that adjustment the operator moves the card-carrier to the right or left, as need be, to position the card laterally with

11

reference to the plunger 23. Those two adjustments determine the position on the card of the first letter or character to be printed.

In order to move the card-carrier to the right the operator must depress and hold down the pushbutton 141 so that fluid can pass the ball check valve 123 and thus return to the reservoir 118. Movement of the card-carrier to the left usually is done in step-by-step fashion by manipulating the actuating arm 24; but it also can be done by holding said arm down and pulling the carrier leftwise through the medium of handle 49. If this is attempted with the actuating arm in the up position the movement will be exceedingly slow and laborious because the piston 120 is in its down position, Fig. 14, and the fluid moving downwardly therethrough can escape only through the greatly constricted lowermost orifice 128 near the bottom end of cylinder 116—the remaining orifices being covered by the piston, as clearly shown in Fig. 14. On the contrary, if the actuating arm is held down the piston 120 will be in the up position with all the orifices 128 uncovered. But unless the aggregate area of the several orifices is large enough to afford a free flow of fluid therethrough it generally is easier to accomplish the leftwise adjustment in the aforementioned step-by-step manner.

Having appropriately positioned the card-carrier, the operator moves the type-case E to bring into registration with the plunger 23 the aperture 22 corresponding to the first letter or character to be printed and then grasps the handle 25, pulling downwardly thereon. This rotates the shaft 103 and quadrant 102 in a clockwise direction, as viewed in Fig. 14, which motion is transmitted through the pitman 105 to the casting 38 and thence to the plunger 23 which descends and, in turn, depresses the type-bar 66, thereby moving the attached type-face into contact with the card.

Coincidentally with downward movement of plunger 23, the movement of roller 153 allows the casting 150 and piston 120 to rise under the impetus of spring 121; and while that is taking place fluid passes from the reservoir 118 through ports 129 and 131 and thence past the ball check valve 123 into the passageway 126, thereby keeping the hydraulic transmission line filled with fluid.

The notches 63 and shoulders 64 are so located that all spacings are correctly proportioned in harmony with each other, having regard to the different widths of the various letters and characters, and it never is necessary to alter the adjustment of screw 165 even when shifting from one type size to another. On the other hand, it often is desirable to depart from what may be regarded as standard by either increasing or decreasing the spacing formula by adding or subtracting a constant. This can be done by rotating screw 165 one way or the other. If the screw is backed off so as to allow more freedom for the ball 164 under the normal condition depicted in Fig. 13, the piston 120 will rise to a corresponding extent before the bellcrank 158 starts rotating, and consequently the piston stroke will be increased, which, of course, means that the spacing is increased. Opposite rotation of screw 165 will give rise to a corresponding decrease. The graduated scale 170 makes it possible to vary the spacing at will and with the utmost accuracy, within certain practical limits.

Completion of a line of printed matter entails, additionally, only repetitions of the steps above

12

described; and each added line obviously involves a rearward movement of the card-carrier, which is effected by means of the knob L and a lateral readjustment of the carrier which is accomplished as before.

As heretofore indicated, it has been one of the principal objects to devise a feed mechanism which is especially suitable for use in conjunction with a printing machine of the kind herein described and will not overthrow, regardless of how vigorously the operator might return the actuating arm to its normal or starting position; and this has been accomplished most successfully by the simple but effective expedient of positioning the orifices 128, Figs. 14 and 15, so that they are progressively closed as the piston 120 descends. As a result, the piston encounters more and more resistance as it approaches the end of each downward stroke and consequently its rate of travel, and that of the driven piston J, is so reduced that the card-carrier and attached parts do not have enough residual momentum to offset the frictional drag of the card-carrier on the surface of the base; and it is impracticable, if not always physically impossible, for the operator to apply enough force to the actuating arm to counteract the increased resistance sufficiently to produce overthrow. One of the arrangements which has been found eminently satisfactory is that depicted in Fig. 15 wherein is shown a series of seven orifices 128 ranging in diameter from .0625" at the top to .024" at the bottom; but that is only one of several obvious alternatives. Manifestly, it would be practicable, for example, to make all the orifices of one small size, say .024", and provide an increasingly greater number of them at successively higher levels, it being immaterial how the orifices are distributed circumferentially of the cylinder. And it would be equally satisfactory and effective to substitute a single elongated discharge port in place of the several orifices 128. It is, of course, important that the braking action be not so excessively prolonged as seriously to diminish the output of the machine.

We have found that the forward movement of the driving piston 120 can be sufficiently checked to prevent overthrow solely as a result of progressive closure of the discharge orifices 128, as hereinbefore described, or by like progressive closure of a single discharge port; but, nevertheless, we consider it desirable, as an extra measure of precaution, so to actuate the driving piston on its forward stroke that the rate at which it is propelled decreases, progressively, irrespective of the retarding effect of the constricted discharge orifices, and this we have accomplished through the medium of the roller 153 acting on the casting 150. In this connection it will be observed that the downward or forward movement of the driving piston may be represented as a sine function, the rate of change of which continuously decreases consonantly with the first derivative of the sine in the third quadrant. Thus, even if the operator increases the pressure exerted on the actuating lever 24 as it approaches the limit of its upward stroke, the resultant amplified angular speed of the lever is more than fully neutralized by the fact that the roller imparts less and less movement to the piston per degree of movement of the roller as the latter approaches the limit of its downward travel.

It also is worthy of note that the means which we have chosen to employ for actuating the driving piston 120, namely, the roller 153 and

quadrant 102, together with the other components which co-operate therewith, is adapted to facilitate ample retractive movement of plunger 23 and the actuated type-bar before any forward movement is imparted to the driving piston. It is necessary that each depressed type-bar be allowed to retract sufficiently to clear the card before any spacing movement is imparted to the card. Otherwise, the printed matter would, obviously, be smeared. To preclude such a happening, the mechanism is so designed that the roller 153 in its up position is elevated to such an extent that it is out of contact with casting 150 even when the spacing control stop mechanism is set to produce the maximum spacing. Therefore, there is always enough lost motion clearance between the roller 153 and the casting 150 to allow the actuated type-bar to rise and clear the card before the driving piston commences its downward travel.

Although we have shown and described but one embodiment, it should be self-evident that the subject invention is susceptible of innumerable modifications and, further, that it has many possible adaptations both within and outside the printing art. Accordingly, we do not wish to be limited as to the scope of our invention otherwise than as prescribed by the terms of the appended claims.

We claim:

1. The combination in a hydraulic motion-transmitting system including a driven piston and a driving piston, of a fluid conduit interconnecting said pistons, a fluid-holding reservoir connected with said conduit by way of a passageway through the driving piston, a check valve in the driving piston effective to allow fluid to pass from the reservoir into the conduit via said passageway and normally effective to prevent passage of fluid in the opposite direction, and means manually operable at will to unseat said check valve whereby to enable fluid to pass the check valve in said opposite direction.

2. The combination in a hydraulic motion-transmitting system including a driven piston and a driving piston, of a fluid conduit interconnecting said pistons, a fluid-holding reservoir connected with said conduit via a passageway through the driving piston, a check valve in the driving piston effective to allow fluid to pass from the reservoir into the conduit via said passageway, and normally effective to prevent passage of fluid in the opposite direction, means manually operable at will to unseat said check valve whereby to enable fluid to pass the check valve in said opposite direction, and stop means for limiting the retractive stroke of the driving piston, said stop means being adjustable in order to predetermine the limit of the retractive stroke of the driving piston whereby to fix in advance the length of forward travel of the driven piston in response to a full forward stroke of the driving piston.

3. The combination in a hydraulic motion-transmitting system including a driven piston and a driving piston, of a fluid conduit interconnecting said pistons, said driving piston having an axial bore, a fluid-holding reservoir connected with said conduit by way of said bore, a check valve within said bore operative to allow fluid to pass from the reservoir to the conduit and to block passage of fluid in the opposite direction, and a rod slidably mounted in said bore and manually operable at will to unseat said check valve

whereby to enable fluid to pass from the conduit to the reservoir.

4. The combination in a hydraulic motion-transmitting system including a driven piston and a driving piston, of a cylinder in which the driving piston is reciprocable, and a fluid conduit interconnecting said driven piston with said cylinder, said cylinder having means forming a discharge port leading from the bore of the cylinder into the conduit, said means being so located and arranged that the port is progressively closed by the driving piston as the driving piston approaches the end of its stroke.

5. The combination in a hydraulic motion-transmitting system including a driven piston and a driving piston, of a cylinder in which the driving piston is reciprocable, a fluid conduit interconnecting said driven piston with said cylinder, said cylinder having means forming a discharge port leading from the bore of the cylinder into the conduit, said means being so located and arranged that the port is progressively closed by the driving piston as the driving piston approaches the end of its pressure stroke, and a passageway extending between the conduit and the bore of the cylinder, forming a by-pass around said port and including a check valve, said check valve being operative to allow fluid to pass through said by-pass only from the conduit to the cylinder bore.

6. The combination in a hydraulic motion-transmitting system including a driven piston and a driving piston, of a cylinder in which the driving piston is reciprocable, a fluid conduit interconnecting said driven piston with said cylinder, said cylinder having means forming a discharge port leading from the bore of the cylinder into the conduit, said means being so located and arranged that the port is progressively closed by the driving piston as the driving piston approaches the end of its pressure stroke, a passageway extending between the conduit and the bore of the cylinder forming a by-pass around said port, and including a first check valve, said first check valve being operative to allow fluid to pass through said by-pass only from the conduit to the cylinder bore, a fluid-holding reservoir, a fluid passageway connected at one end with the reservoir and extending axially through the driving piston, a second check valve carried by the driving piston and interposed in said fluid passageway, said second check valve being normally operative to allow fluid to pass through the said fluid passageway from the reservoir but not in the opposite direction, and means manually operable at will to unseat said second check valve whereby to enable fluid to pass in the opposite direction.

7. The combination according to claim 6 wherein said manually operable means is a rod slidably mounted in the driving piston and extending axially thereof, one end of said rod bearing against the second check valve and the other projecting out of the driving piston to an exterior point.

8. In combination, a hydraulic cylinder having a bore, a piston reciprocable in said bore, said cylinder having an intake port and a discharge port, said piston having a lengthwise passageway establishing communication between said ports, a check valve carried by said piston within said passageway and operative to allow fluid to flow therethrough from the intake port to the discharge port and normally operative to prevent fluid flow in the opposite direction, and a member carried by said piston and reciprocable relatively thereto and manually operable at will to unseat the check

valve whereby to enable fluid to flow through said passageway in said opposite direction.

9. In combination, a hydraulic cylinder having a bore, a piston reciprocable in said bore, said cylinder having an intake port and a discharge port, said piston having a lengthwise axial passageway establishing communication between said ports, a check valve carried by said piston within said passageway and operative to allow fluid to flow therethrough from the intake port to the discharge port and normally operative to prevent fluid flow in the opposite direction, a rod carried by said piston, reciprocable relatively thereto in the axiswise direction, and manually reciprocable at will to unseat said check valve whereby to enable fluid to flow through said passageway in said opposite direction, and a spring biasing said piston axiswise in one direction.

10. In combination, a hydraulic cylinder having a bore, a piston reciprocable in said bore, said cylinder having an intake port and a plurality of discharge ports, said piston having a lengthwise passageway affording communication between the intake port and the discharge ports, a check valve movable with the piston and operative normally to allow fluid to pass through said passageway only in the direction from the intake port to the discharge ports, said discharge ports being spaced at intervals lengthwise of the cylinder so that they are consecutively closed by the piston as the piston approaches the end of its pressure stroke, certain of said discharge ports being of such constricted size as to give rise to substantial resistance to the movement of the piston as it approaches the end of its said pressure stroke.

11. In combination, a hydraulic cylinder having a bore, a piston reciprocable in said bore, said cylinder having an intake port and a plurality of discharge ports, a check valve operative to prevent backflow of fluid through said intake port, said discharge ports being positioned at intervals lengthwise of the cylinder and adapted to be closed consecutively by the piston as the piston moves in connection with its pressure stroke.

12. In combination, a hydraulic cylinder having a bore, a piston reciprocable in said bore, said cylinder having an intake port and a discharge port, a check valve operative to prevent backflow of fluid through said intake port, said discharge port being so positioned that it is progressively covered by the piston as the piston approaches the end of its pressure stroke, the resultant constriction being effective substantially and progressively to retard movement of the latter as the piston approaches the end of its said pressure stroke.

13. The combination in a hydraulic motion-transmitting system, of a first cylinder and a second cylinder, a driven piston reciprocable in said first cylinder, a driving piston reciprocable in said second cylinder, a fluid conduit interconnecting said cylinders, an intake port leading into said second cylinder, a fluid reservoir connected with said intake port, a check valve permitting fluid to pass from the reservoir into the second cylinder and normally effective to prevent backflow of fluid from the second cylinder to the reservoir, an element manually operable at will to unseat the check valve and thus allow fluid to pass therethrough from the second cylinder to the reservoir, and stop means for limiting the retractive stroke of the driving piston, said stop means being movable to selectively pre-set the length of each retractive stroke of the driving piston, individually, thus predetermining the extent of the forward movement of the driven piston in response to a completed forward stroke of the driving piston.

14. The combination in a hydraulic motion-transmitting system, of a driven piston, a driving piston, a fluid conduit interconnecting said pistons whereby a forward stroke of the driving piston is communicated to the driven piston, a fluid intake port leading into said conduit, a check valve effective to allow fluid to enter said conduit through the intake port and normally operative to prevent backflow of fluid through said intake port, and adjustable stop means operative to predetermine the maximum length of each individual forward stroke of the driving piston.

15. The combination in a hydraulic motion-transmitting system, of a driven piston, a driving piston, a fluid conduit interconnecting said pistons whereby a forward stroke of the driving piston is communicated to the driven piston, a fluid intake port leading into said conduit and to an exterior fluid source, a check valve effective to allow fluid to enter said conduit through the intake port and normally operative to prevent backflow of fluid through said intake port, a spring operative to retract the driving piston, a movable stop means operative to predetermine the maximum length of each individual forward stroke of the driving piston, and a manually movable member having a plurality of abutments adapted to be selectively and individually brought into position, through movement of said member, to engage said stop means and limit the movement thereof and, through said stop means, to limit the forward stroke of the driving piston, said abutments being individually so located on said member that the selected abutment determines by virtue of its location the maximum length of the next forward stroke of the driving piston.

16. The combination in a hydraulic motion-transmitting system, of a driven piston, a driving piston, a fluid conduit interconnecting said pistons whereby a forward stroke of the driving piston is communicated to the driven piston, and structure including a plurality of abutments adapted to be brought into operative relation to said driving piston, individually and selectively, the selected abutment being effective to determine the maximum forward stroke of the driving piston, each said abutment being individually located to bring about a piston stroke of specifically predetermined length.

17. In a printing machine of the type that comprises a base, a card-carrier mounted on and movable transversely of the base, a type-case disposed above the base and mounted for universal movement in a horizontal plane, a plurality of vertical type-bars supported by the case and spaced apart horizontally, each type-bar having a type-face at its lower end positioned to contact a card on the base therebelow when the type-bar is depressed, said type-case including a top member having a plurality of apertures in vertical alignment with said type-bars individually, said top member having also a plurality of shoulders, each associated individually with one of said apertures and its related type-bar and each spaced from its associated aperture transversely of the base to an individually predetermined extent, a vertical plunger operative upon downward movement to enter said type-case apertures, individually, whereby to engage and depress the individually associated type-bars, and a lever arm for actuating the plunger; a hydraulic motion-transmitting system for moving the card-carrier fol-

lowing each actuation of a type-bar by the said plunger, in the direction effective to accomplish proper spacing between the letters or characters forming a given line, and spacing control mechanism associated with the system and effective automatically to predetermine the extent of the aforementioned spacing movement of the card-carrier, following each actuation of a type-bar, in accordance with the location of the shoulder individually associated with the last-actuated type-bar, said motion-transmitting system comprising a driven piston drivably connected with the card-carrier, a first cylinder in which said piston is reciprocable, a driving piston, a second cylinder in which said driving piston is reciprocable, a fluid conduit interconnecting said cylinders, a fluid-holding reservoir connected with the conduit through a check valve and operative to feed fluid to the conduit during each retractive stroke of the driving piston, said check valve being normally effective to prevent backflow of fluid to the reservoir, and means controlled by movements of the lever arm for reciprocating the driving piston, said spacing control mechanism comprising a movable stop, the position of which is determined by the shoulder associated with the last-actuated type-bar and which, in turn, determines, in accordance with its position, the limit of the retractive stroke of the driving piston and thus the length of the succeeding forward stroke of said driving piston.

18. A printing machine as set forth in claim 17 wherein the second cylinder of the hydraulic motion-transmitting system is provided with means forming discharge port which leads into the conduit, extends through the cylinder wall and is adapted to be progressively closed by the driving piston as the latter approaches the end of each pressure stroke, so that the discharge of fluid from said second cylinder becomes greatly retarded before the driving piston reaches the end of its said pressure stroke.

19. A printing machine as set forth in claim 17, wherein the second cylinder of the hydraulic motion-transmitting system is provided with a plurality of discharge ports leading into the conduit and spaced at intervals lengthwise of the cylinder so that they are closed consecutively by the driving piston as it approaches the end of its pressure stroke, said ports being so proportioned that the movement of the driving piston is substantially and progressively retarded as it approaches the end of each pressure stroke.

20. A printing machine as set forth in claim 17, including a rotatable shaft which is connected to be rotated by movements of the lever arm and is operatively associated with both the plunger and the driving piston so that rotation of the shaft in one direction lowers the plunger and causes retraction of the driving piston and vice-versa.

21. A printing machine as set forth in claim 17, including a spring biasing the driving piston retractively, a shaft connected for rotation by the lever arm, and means drivably interconnecting said shaft with the driving piston and the plunger so that rotation of the shaft in one direction effects a retraction of the driving piston and a downward movement of the plunger, opposite rotation of the shaft being effective to move the driving piston forwardly and to move the plunger upwardly.

22. A printing machine as set forth in claim 17, wherein the spacing control mechanism comprises a bellcrank having two arms, one of which functions as a movable stop to limit the re-

tractive stroke of the driving piston, and a dog pivotally connected to the distal end of the other bellcrank arm and operative to engage that selected one of the said shoulders which is associated with a type-bar in registration with the said plunger, said bellcrank being rotatable in response to a retractive stroke of the driving piston to move said dog into engagement with the selected shoulder, the engagement of the dog with the shoulder being effective to terminate the rotation of the bellcrank and, resultantly, to terminate the retractive stroke of the driving piston.

23. A printing machine as set forth in claim 22, including an adjusting screw carried by the bellcrank and operative to shift the bellcrank rotationally in relation to the driving piston to alter the stroke of the driving piston independently of the limit determined by the shoulder engaged by the dog.

24. A printing machine as set forth in claim 22, wherein the bellcrank arm has a pocket at its distal end, a ball located in the pocket and positioned thereby, said ball serving as a stop member for limiting the retractive stroke of the driving piston, and an adjusting screw carried by the bellcrank, one end of said screw forming a backstop for the ball, said screw being operative conjointly with the ball to shift the bellcrank rotationally in relation to the driving piston to alter the stroke of the driving piston independently of the limit determined by the shoulder engaged by the dog.

25. A printing machine according to claim 22, wherein the bellcrank is fulcrumed for rotation in a vertical plane and is located above the type-case and wherein the bellcrank arm which carries the dog depends substantially vertically from its fulcrum center, and including a backstop for the dog which serves to rotate the dog out of engagement with the type-case when the dog is retracted.

26. A printing machine according to claim 25, including a vertically slidable rod spring-pressed downwardly and operative to engage the dog and press the same into engagement with the top surface of the type-case, and a member carried by said plunger and operative during the upstroke of the plunger to lift said rod, thereby relieving the dog of the pressure of the rod while the dog is in engagement with its backstop.

27. In a printing machine of the type that comprises a base, a card-carrier mounted on said base and movable thereover in a horizontal plane, a type-case mounted for universal movement in a horizontal plane above said card-carrier, a plurality of vertical type-bars housed within said type-case, each type-bar having a type-face at its lower end and each provided with a biasing spring which normally supports it in an elevated position, and a vertically reciprocable plunger disposed above the type-case and normally held in an elevated position, said plunger being movable downwardly to engage and depress said type-bars individually and selectively: a hydraulic motion-transmitting mechanism operative to move the card-carrier intermittently for spacing consecutive printed letters or characters, said mechanism including a first cylinder, a driven piston reciprocable in said first cylinder and drivably connected to the card-carrier, a second cylinder, a driving piston reciprocable vertically in said second cylinder, a spring biasing said driving piston retractively, a fluid conduit interconnecting said cylinders, a check valve, a fluid-holding reservoir connected with said conduit

through said check valve, said check valve being operative to allow fluid to pass from the reservoir into the conduit during each retractive stroke of the driving piston and to prevent backflow of fluid during each forward stroke of the driving piston, a member attached to and carried by the driving piston above the second cylinder and having a horizontal top surface, a horizontal shaft located above said member and journaled for rotation, a lever carried by said shaft for manually rotating the same reciprocably between two limiting angular positions, a quadrant rotatable with said shaft, a roller carried by said quadrant and normally engaging the said top surface of said member, in which position it is effective to hold the driving piston at the limit of its forward stroke against the opposition of its biasing spring, said roller being movable upwardly in an arcuate path in response to a rotation of said shaft away from its normal posture of rest to allow the driving piston to retract upwardly under the impetus of its biasing spring, said plunger being drivably connected with said quadrant to effect downward movement of the plunger concurrently with retractive upward movement of the driving piston, and an adjustable stop effective to engage said member and thereby limit the upward stroke of the driving piston, the arrangement being such that the limit of the retractive stroke of the driving piston is independent of said roller and thus capable of being varied in harmony with each individual spacing requirement.

28. A printing machine according to claim 27, characterized in that the adjustable stop comprises a bellcrank having a horizontal arm and a vertical depending arm, the distal end of said horizontal arm overlying the top surface of said member and engaged therewith, said type-case including a plurality of abutments, each individually associated with one of said type-bars, said machine further including a dog pivotally connected to the distal end of the depending bellcrank arm, said dog being movable with said bellcrank in response to a retractive movement of the driving piston and adapted upon such movement to engage the abutment corresponding to a selected type-bar, the engaged abutment being effective to block further movement of the dog and bellcrank and thus to terminate the retractive movement of the driving piston.

29. The combination in a hydraulic motion-transmitting system, of a driven piston, a first cylinder for said driven piston, a driving piston, a second cylinder for said driving piston, a fluid conduit interconnecting said cylinders, said driving piston having an axial passageway connected at one end with said conduit, a fluid source connected with the other end of said passageway, a check valve carried by said driving piston within said passageway, said check valve being operative to pass fluid from said source through said passageway during each retractive stroke of the driving piston and normally effective to prevent backflow therethrough, a rod carried by the driving piston and slidably axially thereof, one end of said rod being adapted to engage and unseat said check valve upon depression of the rod, the other end of the rod projecting outwardly from the driving piston, a tubular shaft extending perpendicularly to the axis of the driving piston, means carried by said shaft for actuating said driving piston in response to rotation of the shaft, a bar within the bore of said tubular shaft and extending axiswise thereof and rotatable relatively to the shaft, a first finger

carried by said bar and projecting radially therefrom and operative upon rotation of said bar in one direction to engage and depress said rod whereby to unseat the check valve, a lever carried by said shaft for effecting manual rotation thereof, a second finger carried by said bar and projecting radially therefrom adjacent said lever, and a plunger carried by said lever and extending lengthwise thereof, one end of said plunger being positioned to engage said second finger and thereby rotate said shaft in the direction to unseat said check valve in response to a depression of said plunger.

30. The combination according to claim 29 including a spring for retracting the driving piston, and an element actuated by said shaft for propelling the driving piston forwardly against the opposition of said spring in response to a rotation of the shaft in one direction.

31. The combination in a hydraulic motion-transmitting system, of a first cylinder, a driven piston reciprocable in said first cylinder, a second cylinder, a driving piston reciprocable in said second cylinder, a fluid conduit including said cylinders interconnecting said pistons, said second cylinder having a discharge port arranged to be progressively covered by the driving piston as the latter approaches the limit of its forward stroke, and manually operable means for actuating the driving piston, said means comprising a manually rotatable shaft and mechanism driven by said shaft and operative, in turn, to propel the driving piston forwardly, said mechanism being effective to transmit forward motion to the driving piston at a progressively decreasing speed in response to rotation of said shaft at a uniform speed.

32. The combination according to claim 31 wherein the specified mechanism comprises a rotary cam designed to transmit forward motion to the driving piston at a progressively decreasing rate.

33. In a printing machine of the type that comprises a base, a card-carrier mounted on said base and movable thereover step-by-step in a rectilinear path to effect spacing between consecutive printed letters, a type-case mounted above the carrier and movable thereover in a horizontal plane, a plurality of vertical type-bars within said case, each having a type-face at its lower end, and a vertical plunger operative upon downward movement to engage and depress said type-bars individually and selectively, a hydraulic motion-transmitting system operative to move the card-carrier a predetermined distance during each upward movement of the plunger, said mechanism including a driven piston connected to the carrier, a first cylinder in which the driven piston is reciprocable, a driving piston, a second cylinder in which the driving piston is reciprocable, a fluid conduit interconnecting said cylinders, a reservoir connected with said fluid conduit through a check valve which normally is operative to prevent backflow of fluid from the conduit to the reservoir, and a manually operable mechanism for actuating both said plunger and said driving piston, said mechanism including an element operative to propel the driving piston forwardly during each upstroke of the plunger, there being a lost-motion separation between said element and the driving piston when the plunger is in its downmost position, which lost-motion separation is effective to allow the plunger to rise a

21

predetermined distance before said element becomes effective to propel the driving piston.
